UNITED STATES PATENT OFFICE.

GEORGE H. BENEDICT, OF NEW YORK, N. Y.

DESIGN FOR A PACKAGE-HOLDER.

SPECIFICATION forming part of Design No. 18,036, dated February 7, 1888.

Application filed December 23, 1887. Serial No. 258,852. Term of patent 7 years.

To all whom it may concern:

Be it known that I, GEORGE H. BENEDICT, of the city, county, and State of New York, have invented a new and original Design for a Package-Holder; and I do hereby declare that the following is a full and exact description thereof, reference being had to the accompanying drawing, and to the letters of reference marked thereon.

10 My invention consists in a novel and ornamental form imparted to a package-holder by producing hooks at the ends of a straight handle, each having parallel arms united by a semicircular curve and terminating in a re-
15 entrant circular curve at the end of its outer arm approximating closely the inner straight arm.

In the accompanying drawing, D E and D E represent the hooks, and C the interposed straight handle, of a package-holder. The main stem or inner arm, D, of each hook is straight, or nearly so. The lowerend, f, of the hook is in the general form of a semicircle.

Its outer arm, E, extending from the arc of the lowercurve, f, of the hook, is parallel with 25 the opposite arm D, and terminates in an inward bend, K, circular in form, and which approaches more or less closely the main stem D of the hook.

I claim as my invention—

30 The design for a package - holder herein shown and described, the same consisting of the straight handle C, terminating at each end in a straight inner arm, D, at a right angle thereto, a straight outer arm, E, parallel with 35 the arm D, a semicircular return-bend, f, connecting the two, and a circular inward bend, K, approximating the inner arm, D, at the end of the outer arm, E.

In testimony whereof I have signed my name 40 to this specification in the presence of two subscribing witnesses.

G. H. BENEDICT.
